DESIGN FOR A COMBINED AUTOMATIC
TYPEWRITER AND STANDOtto Kuhler, Grantwood, N. J., assignor to Automatic Business Machines, Inc., Pittsburgh, Pa., a corporation of Delaware

Application February 4, 1936, Serial No. 60,971

Term of patent 14 years

To all whom it may concern:

Be it known that I, Otto Kuhler, a citizen of the United States, residing at Grantwood, Bergen County, New Jersey, have invented a new, original, and ornamental Design for a Combined Automatic Typewriter and Stand, of which the following is a specification, reference being had to the accompanying drawing, forming a part hereof.

In the drawing:

The dominant feature of the design resides in the stand shown.

I claim:

The ornamental design for a combined automatic typewriter and stand as shown and described.

OTTO KUHLER.
